HIGHWAY MARKER

Wayne B. Thompson, Winchester, Mass., assignor
to Spray Engineering Company, Somerville,
Mass., a corporation of Massachusetts

Application July 21, 1931, Serial No. 552,178

9 Claims. (Cl. 91—45)

The present invention relates to marking devices which are caused to travel over a highway and mark a traffic line thereon.

The principal object of the present invention is

5 to produce a marker with which the highway may be provided, either continuously or intermittently, with a traffic line or stripe having a predetermined width, sharply defined edges and a smooth, even surface.

10 To the accomplishment of this object, and such others as may appear hereinafter, the various features of the present invention reside in certain constructions and arrangements of parts hereinafter described and then set forth in the 15 appended claims which possess advantages readily apparent to those skilled in the art.

The various features of the present invention will be understood readily from an inspection of the accompanying drawings illustrating the best 20 form of the invention at present devised, in which,

Figure 1 is a view in right side elevation of the highway marker;

Fig. 2 is a view in plan;

25 Fig. 3 is a view in rear elevation, the handles being in section;

Fig. 4 is a detail view in sectional elevation of one of the wheel and disk units together with the supporting structure therefor;

30 Fig. 5 is a detail view in right side elevation, partly in section, showing the mounting for the spray gun, one of the disks, and the scraper, spoon and pan associated therewith;

Fig. 6 is a detail view in plan of a slip sleeve 35 for one of the wheel disk unit axles, and

Fig. 7 is a detail view in sectional elevation on the line 7—7, Fig. 3.

In the illustrated embodiment of the invention the traffic line is marked on the highway by a spray gun 7 (Fig. 5), the spray from which is confined to a stripe 8 (Fig. 2) of predetermined width by shields comprising two disks 9 and 10 (Fig. 3). The spray gun, as indicated in Fig. 5, is one of the Spraco type disclosed in my Patent No. 1,706,006, March 19, 1929. The disk 9 (Fig. 4) is secured to the reduced squared end of a stub shaft or axle 11 which is journaled in a slip sleeve 12. One end of the sleeve 12 engages a collar 13 secured to the reduced portion of the axle. The other end of the sleeve 12 engages the disk 9. The disk 9 is secured in position on the axle and in engagement with the sleeve 12 by a cap screw 14 threaded into one end of the axle, there being a washer 15 interposed between the disk 9 and the head of the cap screw. With this

construction the disk 9 rotates with the axle 11. The reduced portion of the axle 11 is provided with a second collar 16. As shown in Fig. 4, shoulders on the collars 13 and 16 support a rubber tired wheel 17 which is held in position by a nut 18 threaded onto one end of the axle 11.

The other disk 10 is associated with a rubber tired wire wheel 19 (Fig. 3). The disk 10 rotates with the axle upon which the wheel 19 is mounted in a manner similar to the disk 9. The axle for 10 the wheel 19 is rotatably mounted in a slip sleeve 20 (Fig. 3) similar to the sleeve 12. As shown in Figs. 3 and 5 the disks 9 and 10 are smaller in diameter than their associated wheels 17 and 19. With this construction the disks clear the 15 highway and permit the marking of crowned portions thereof.

The sleeves 12 and 20 are mounted, respectively, in bearings 21 and 22 (Fig. 3) which are secured by bolts 23 (Fig. 4) to the side frames 20 24 (Fig. 2). The side frames 24 are connected by a plate 25 (Fig. 2) which has the additional function of counterbalancing the weight at the rear end of the highway marker. At their front ends the side frames 24 support a horizontal rod 26 (Figs. 1 and 2) the opposite ends of which form bearings for the rubber tired wheels 27. Pivoted to the rod 26 is a yoke frame 28 the free ends of which support rotatably a small roll 29 mounted to roll over the highway and indicate the location of the center line of the stripe.

As shown in Fig. 3, the bearings 21 and 22 support the feet of a bridge 30. Secured to the sides of the bridge 30 are two rods 31 the upper ends of which carry a head 32 provided with a 35 vertical hollow boss 33. Mounted in the boss 33 is the stem of a clamp 34 receiving a yoke 35 provided at its free ends with rotatable sleeves 36 and 37 covered, respectively, with rubber grips 38 and 39.

40 The spray gun 7 is mounted centrally between the disks 9 and 10 with its discharge orifice directed downwardly. To this end the handle of the spray gun is positioned in a recess 40 (Figs. 3 and 5) formed on one face of a casting 41 the upper end of which is secured by a pair of cap screws 42 to an arm 43. At its upper end the arm 43 is split to embrace a rod 44 depending from the bridge 30. The arm 43 may be secured in any desired position of adjustment on the rod 50 44 by a bolt 45 passed through the split portion of the arm 43. The handle of the spray gun is clamped in the recess 40 by a plate 46 secured to the casting 41.

45 The spray gun receives its coating material 55

through a flexible conduit 47 (Fig. 5) which conducts the coating material from a tank (not shown) on a truck travelling at a slow pace on the highway. The truck carries also a supply of compressed air which is connected through a flexible conduit 48 (Fig. 3) to a T 49 supported by a short pipe 50 carried by the head 32. The T 49 is connected by a flexible conduit 51 to the handle of the spray gun.

As well known to those skilled in this art, the flow of the compressed air and coating material through the spray gun is controlled by valves (not shown) operatively connected to a trigger 52 (Fig. 5) on the spray gun. In order to operate the trigger it is engaged by a small roll 53 on one arm of a bell-crank lever 54 pivotally mounted on a horizontal pin 55 carried by the casting 41. The bell-crank lever 54 is provided also with a small roll 56 which engages one end of a piston 57 mounted to slide in a cylinder 58 on the casting 41. The interior of the cylinder 58 receives compressed air from a flexible conduit 59 (Figs. 3 and 5) connected to a three-way valve 60 secured to the bottom of the pipe 50. The three-way valve is constructed to control the passage of air from the pipe 50 into the flexible conduit 59. When the three-way valve is in one position the compressed air enters the cylinder 58 and moves the piston 57 outwardly to operate the trigger in a direction to open the coating material and compressed air valves in the spray gun.

In order to limit the movement of the trigger 52 under the influence of the piston the bell-crank lever 54 is provided with an offset tail 61 (Figs. 3 and 5) arranged to engage one end of a screw 62 adjustably secured on a lug formed on one side of the casting 41. In order that the three-way valve 60 may be controlled by the operative the stem 63 of the valve is squared (Fig. 3) to receive one end of a wrench 64. The other end of the wrench 64 is connected by a rod 65 to an arm 66 integral with the right hand rotatable sleeve 36 (Fig. 3). When the three-way valve 60 is closed a pin 67 on one side of the stem 63 engages a shoulder 68 on the valve body. When the operative rotates the sleeve 36 in a clockwise direction, viewing Fig. 3, the three-way valve is opened and air is admitted through the conduit 59 to the cylinder 58 to operate the trigger 52 and the valves of the spray gun. The opening movement of the valve is limited by a shoulder 69 arranged on the valve body in a position to be engaged by the pin 67. When the sleeve 36 is rotated thereafter in a counter-clockwise direction the three-way valve is closed and the air in the conduit 59 is vented through a vent 70 (Fig. 1), thus permitting the usual valve closing springs in the spray gun to return the trigger 52 and the piston 57 to their normal inoperative positions.

In order to vary the width of the spray defined by the disks 9 and 10 the sleeves 12 and 20 therefor are adjustable towards and from each other in the bearings 21 and 22, respectively. To this end the bearings are split so that by releasing cap screws 71 (Fig. 2) therein the embraced sleeves 12 and 20 may be slid in the bearings towards and from each other. As shown in Figs. 3 and 6 the sleeves 12 and 20 are provided with a series of peripheral grooves 72 marked, respectively, 4, 5, 6, 7 and 8. These marks indicate the number of inches separating the disks 9 and 10 and consequently the width to be given the stripe. As shown in Fig. 3 the sleeves 12 and 20 are adjusted in their bearings to register the six inch

scores with the inside faces of the bearings. Thus, the disks 9 and 10 are separated a distance sufficient to define a stripe 6 inches wide on the highway. The height of the discharge orifice of the spray gun above the highway may be correlated with the distance separating the disks 9 and 10 by raising and lowering the arm 43 on the rod 44. Experience has demonstrated that, with the Spraco spray gun 1, the height of the discharge orifice above the highway should be commensurate substantially with the width of the stripe. That is, the vertical distance from the highway to the discharge orifice of the spray gun should be substantially the same as the horizontal distance between the disks 9 and 10. It will be understood by those skilled in this art, however, that this vertical distance may vary depending upon the coating material or the type of spray gun or nozzle used.

In order to maintain the peripheries and inside faces of the disks 9 and 10 free from accumulations of marking material which may splash thereon, the highway marker is provided with scrapers which scrape the disks during their rotation and with spoons which receive the scraped material from the scrapers and deposit it centrally upon the stripe formed on the highway. To this end the side frames 24 are provided with U-shaped bolts 73 (Figs. 2, 3 and 5) which clamp a horizontal rod 74. Loosely mounted on the rod 74 are two collars 75 and 76 one of which is associated with the disk 9 and the other one of which is associated with the disk 10. As the construction and mode of operation of the collars and the parts supported thereby are identical the description thereof will be restricted to the scraper and spoon construction associated with the disk 10 (Fig. 5).

The collar 75 supports an arm 77 (Fig. 5) having an offset upstanding end 78. Clamped to the offset end 78 is a scraper unit comprising a wiper 79 clamped between two holder plates 80. The wiper is arranged at an inclination with one edge face engaged with the inside face of the disk 10. The marking material scraped off the disk 10 by the wiper 79 drops upon a spoon 81 secured to the bottom of the arm 77. The upper face of the spoon 81 is dished to form a trough for the collected coating material. The free end of the spoon 81 toes inwardly (Fig. 3) so that the collected coating material may be discharged towards the center of the stripe.

The peripheral edge of the disk 10 is scraped by a piece of leather 82 (Figs. 3, 5 and 7) which is interposed between one edge face of the spoon 81 and a plate 83. The plate 83 is held in position by two screws 84 which engage the plate 83, pass through the leather block 82, and are threaded into the adjacent face of the spoon 81. The leather block 82 scrapes the peripheral edge of the disk 10 clean, the scrapings falling also into the spoon 81. As indicated in Figs. 5 and 7 the effective leading edge 85 of the leather block 82 is arranged in the same plane as the wiper 79 thus to insure that the scrapings from the block and wiper will fall into the spoon 81.

The scrapers 79 and 82 are held in the position shown in Fig. 5 by a spring 86 coiled about the rod 74. One end of the spring 86 is secured to a collar 87 (Fig. 3) secured to the rod 74. The other end of the spring 86 is hooked on one face of the arm 77 (Figs. 4 and 5). The loose collar 75 is backed up by a collar 88 secured to the rod 74. By loosening the collars 87 and 88 the wipers 79

and 82 may follow the lateral adjustment of the disks.

It is often desirable to form a broken traffic line on the highway but heretofore this could not be done with a travelling marker, either of the spray gun or brush type. In order to form a broken traffic line the three-way valve 60 is closed by manipulating the sleeve or handle 36 thus stopping the discharge of spray from the spray gun. Shortly before stopping the operation of the spray gun a catch-pan 89 (Figs. 3 and 5) is swung under the discharge ends of the spoons 81 to receive the scraped marking material therefrom. The pan 89 is provided with a bottom dished in the direction of its width to form a trough in which the coating material discharged by the spoons may accumulate without danger of spilling upon the highway. Centrally the pan 89 is provided with a spillway 90, but this spillway is formed above the trough so that the contents thereof may not pass through the spillway while the pan occupies the position shown in full lines in Fig. 5.

One end of the pan 89 is secured to the lower end of a lever 91 pivoted at 92 on the left-side frame 24, viewing Fig. 2. The upper end of the lever 91 is pivoted to the lower end of a rod 93 (Fig. 3) the upper end of which is pivoted to an arm 94 projecting laterally from the sleeve 37. The other end of the pan 89 is secured to the lower end of an arm 95 (Fig. 3) pivoted at 96 on the right side frame 24. The pivots 92 and 96 are arranged in the same horizontal and vertical planes.

Under normal operating conditions the pan 89 is swung back into the construction line position of Fig. 5 while the highway is being marked with the stripe 8. About three feet before the point is reached where the spray is to be shut off and thus end the mark on the highway, the pan 89 is swung into the full-line position of Fig. 5 in which position it is left while traversing a gap in a broken line or while the highway marker is not in operation. If it is intended to form a gap in the line the valves in the spray gun are reopened to restart the spray after the proper interval, but the pan 89 is left in its down position until a new stripe 8 substantially three feet in length is formed when the pan 89 is swung into the construction line of Fig. 5. When the pan 89 containing the accumulation of scrapings from the spoons 81 is moved into the construction line position of Fig. 5, the scrapings flow out of the spillway 90 upon the center portion of the stripe. By moving the pan 89 into its down position before the end of the line is reached and by moving it into its up position after the new line is started the excess paint from the faces and peripheral edges of the disks is prevented from dripping on any unmarked portion of the highway.

In the event a traffic line on the highway is to be remarked a gage 97 is registered with one edge of the old stripe in the manner indicated in Fig. 2. The gage 97 is adjustably mounted on a plate 98 carried by the frame 28.

By mounting the wheels 16 and 19 on separate axles, respectively, the operative may tip the highway marker backwardly to elevate the wheels 27 from the highway and turn the highway marker on one of the wheels 16 and 19 as an axis to cause the spray gun to spray along a curved line. In turning the highway marker to follow a curved line the wheel and disk on one side are free to rotate forwardly while, it may be, the wheel and disk on the other side are free to rotate backwardly.

The handles 38 and 39 are grasped as the operative pushes the highway marker along the highway permitting the operative at the same time to control the admission of air into and out of the cylinder 58, the raising and lowering of the catch pan 89, the tipping of the highway marker, and its turning on one of the wheels as a pivot.

It will be clear to those skilled in the art, and with the general objects of the present invention in view, that changes may be made in the details of structure, the described and illustrated embodiment thereof being intended as an exploitation of the underlying essentials of the invention, the features of which are definitely stated in their true scope in the claims presented herewith.

What is claimed as new is:

1. In a highway marker, the combination with a carriage having four wheels the rear ones of which are mounted upon independent slidably movable axles, and a spray gun mounted on the carriage to discharge marking material towards the highway, of shields mounted on said axles, respectively, for confining the application of the marking material on the highway to a stripe of predetermined width.

2. In a highway marker, the combination with a spray gun for discharging marking material towards the highway and independent shields for confining the application of the marking material on the highway to a stripe of predetermined width, of means for scraping excess marking material from the shields and dumping it upon the stripe.

3. In a highway marker, the combination with a spray gun for discharging marking material towards the highway, rotating disks for confining the application of the marking material on the highway to a stripe of predetermined width, means for removing excess marking material from the inside faces and peripheral edges of the disks, and means for catching and storing the excess marking material removed from the disks, of means for dumping the stored marking material upon the stripe.

4. In a highway marker, the combination with a rotatable disk, a scraper for removing excess marking material from one face of the disk and a spoon for conducting the excess marking material removed from the disk to a point on the highway spaced from the said face of the disk, of a pan movable to a position beneath the spoon to receive therefrom said excess material.

5. In a highway marker, the combination with a rotatable disk, scrapers for removing excess marking material from one face of the disk and the peripheral edge of the disk, and a spoon for conducting the excess marking material removed from the disk to a point on the highway spaced from said face of the disk, of a pan movable to a position beneath the spoon to receive therefrom said excess material.

6. A highway marker having, in combination, a disk, a wiper for scraping one face of the disk, a spoon for catching the scrapings and conducting them to a point remote from the scraped face of the disk, a wiper carried by the spoon for scraping the peripheral edge of the disk, an arm supporting the first named wiper and the spoon, a rod upon which the arm is loosely mounted and a coiled spring having one end engaged with the arm and the other end supported from the rod for pressing the wipers against the inside face and the peripheral edge of the disk, respectively.

7. In a highway marker, the combination with

- a wheeled carriage, a spray gun mounted thereon for discharging marking material towards the highway, shields for confining the application of marking material on the highway to a stripe of predetermined width, means for removing excess material from the shields and dumping it upon the stripe, a pan movable into a position to receive the removed excess material, rotatable handles carried by the carriage engaged by the operative in wheeling the carriage over the highway, and means controlled by the rotation of the handles for controlling the operation of the spray gun and the pan.
8. In a highway marker, the combination with a spray gun for discharging marking material towards the highway, rotatable disks for confining the application of the marking material on the highway to a stripe of predetermined width,

means for removing excess marking material from the disks, and means for catching and storing the excess marking material removed from the disks, of means for dumping the stored marking material upon the stripe at a point spaced 5 from the edges of the stripe.

9. In a highway marker, the combination with a spray gun for discharging marking material towards the highway, rotating disks for confining the application of the marking material on the 10 highway to a stripe of predetermined width, means for removing excess marking material from the inside faces of the disks, and means for catching and storing the excess marking material removed from the disks, of means for 15 dumping the stored marking material upon the stripe.

WAYNE B. THOMPSON.
